MACHINE AND STOP MOTION THEREFOR

Arthur R. Havener, Wayland, Mass., assignor to
 Judson L. Thomson Manufacturing Company,
 Waltham, Mass., a corporation of Massachusetts

Application July 10, 1941, Serial No. 401,738

7 Claims. (Cl. 218—0.5)

This invention relates to machines for performing repetitive cycles and to stop motions for the same, and has for an object to provide mechanism for controlling the machine mechanism by which when desired the machine may act through a predetermined number of cycles and then stop automatically, or which may be stopped at the completion of any intermediate cycle, or controlled to operate in a single cycle, at the will of the operator.

A further object is to provide a single control member by manipulation of which each of these controls may be made effective.

For a more complete understanding of this invention, reference may be had to the accompanying drawings in which

Figure 1 is a fragmentary front elevation of a duplex riveting machine embodying the invention.

Figure 2 is a detail section of the same on line 2—2 of Figure 1.

Figure 3 is a fragmentary side elevation of the machine.

Figure 4 is a fragmentary rear elevation of the same showing the clutch actuating mechanism.

Figure 5 is a fragmentary perspective view of the clutch control lever and a controlling cam therefor.

For the purpose of illustration this invention has been shown embodied in a duplex riveting machine with an indexing anvil turntable of the type shown in my Patent No. 1,850,671, granted March 22, 1932, to which patent reference may be had for detailed description of the riveting mechanism.

For understanding of the present invention it is sufficient to point out that the machine includes a frame 1 provided with a head 2 carrying a plurality of riveting mechanisms indicated generally at 3 and each being supplied with rivets from a feed hopper 4. Each of the riveting mechanisms is provided with a rivet driver 5 pivotally connected at 6 to the forward end of an actuating lever 7. Each lever 7 is fulcrumed at 8 on a link 9 pivoted at 10 to the machine frame 1 and to the rear end of each lever 7 is secured the upper end of a link 11. These links 11 are connected for up and down motion as is illustrated in my previous Patent No. 1,850,671 for actuation by the rotation of a drive shaft 12. Such connections may include eccentrics secured to the drive shaft 12 to which the links 11 are connected.

This drive shaft 12 has journaled thereon a drive wheel 13 over which may be passed a driving belt 14, and the shaft 12 and drive wheel 13 may be connected by one revolution clutch 55

mechanism, indicated generally at 15 which may be of the type shown in my Patent No. 1,730,140, granted October 1, 1929. When a locking member 16 of the clutch is released by moving a slide 17 to the right (see Figure 4), the locking member 16 locks the two parts of the clutch together so that the drive shaft 12 is rotated. The slide 17 is moved toward the right by a lever 18 and pawl 19, the lever 18 being fixed to a rock shaft 20. This rock shaft 20 is connected to a controlling element as will later appear. A spring 21 moves the slide 17 to the left when this is permitted by the controlling member, whereupon this slide 17 will be engaged by the locking member 16 of the clutch, disengaging the clutch members from each other so that the shaft 12 comes to a stop while the belt pulley 13 continues to be driven by the belt 14. At each retraction of the slide 17 the clutch is connected for one revolution and if when the locking member 16 has completed its rotation, the slide 17 is in position to engage it, the clutch is opened after a single cycle of operations of the machine. Should the slide 17 be held retracted from the path of the locking element 16, the clutch will continue to be closed while the machine continues to repeat the cycle of operations.

Beneath the machine head 2 the bed of the machine is shown as provided with a bracket 25 within which is journaled a vertical shaft 26 secured at its upper end to an indexing turntable 27. This indexing turntable is arranged to be moved step by step between successive machine operations. The means for doing this may be substantially as shown in my Patent No. 1,850,671 and comprises a horizontal slide 70 to which is pivoted at 71 an inwardly spring pressed indexing dog 72 provided with a notched end 73 adapted to engage successively with indexing pins 74 projecting in circular array about its axis from the lower face of the turntable 27. Each outward motion of the slide 70 causes the dog 72 to engage one of these pins 74 and push it and the turntable around through an angular distance corresponding to the angular spacing of the anvils 28. A locking pawl 75 mounted and functioning precisely like the pawl 113 of my Patent No. 1,850,671 holds the turntable stationary between indexing motions. The slide 70 is reciprocated by mechanism driven by the main shaft, such mechanism comprising a bell crank lever 76 fulcrumed at 77, one arm being connected by the link 78 with the rear portion of the slide 70 and the other by a link 79 with a crank pin 80 on a crank disk 81 on the main shaft.

The turntable 27 carries a plurality of rivet set mechanisms 28 arranged in circular series thereon and so arranged with respect to the rivet drivers that a pair of rivets are driven simultaneously at diametrically opposite sets simultaneously, whereupon on retraction of the drivers, the turntable is indexed to bring the next adjacent anvils or sets into position. It will thus be seen that during each half revolution of the turntable all of the setting devices have been presented to the drivers to set rivets in the work (not shown) supported on the turntable 27, so that the desired number of rivets to be driven in the piece of work supported on the turntable is complete.

Provisions are made in accordance with this invention, therefore, for continuing the operation of the machine, after it has once been started, through the complete cycles necessary to set all the rivets in the work supported on the work holder. Occasionally, however, it may be desired to provide for a single actuation of the rivet setting devices and it is also desirable that means be provided for stopping the machine at the end of any individual cycle prior to the completion of the full number required to complete the riveting of one work piece. To this end the shaft 26 has secured to its lower end a control cam 30 provided with a peripheral groove 31 opened out to the lower end of the cam as through a pair of diametrically opposite slots 32. Cooperating with this cam is a clutch control arm 33. This control arm as shown is provided with a pin 34 which may ride in the peripheral groove 31 of the cam and may be caused to pass downwardly through either of the slots 32. This control lever 33 is fulcrumed at its rear portion on a vertical pivot 37 for limited horizontal motion in a block 38 which is fixed to a rock shaft 39 as by a pin 40 (see Figure 2). This rock shaft 39 is journaled in spaced bearings 41 and 42 and is held against axial motion as by a pair of collars 43 and 44 pinned thereto outwardly of the bearings 41 and 42. Adjacent to the collar 44 the rock shaft 39 has secured thereto a crank arm 45 to the rear end of which is pivoted, as at 46, the lower end of a link 47 which may be provided intermediate its ends with a turnbuckle 48 by means of which its effective length may be adjusted. The upper end of the link 47 is pivoted between ears 50 of a crank arm 51 fixed to the rock shaft 20. Thus when the outer end of the controlling lever 33 is depressed to bring the pin 34 down through one of the slots 32 to ride beneath the cam 30, as in the dotted line position of Figure 3, the arm 45 is lifted, lifting the link 47 and rocking the shaft 20 into position to retract the slide 17, thus permitting the clutch parts to engage and start the drive of the rivet actuating shaft 12. A horizontal spring 55 engaging the control lever 33 tends to hold this control lever rocked to one limit of its motion about the fulcrum 37, such as to hold the pin 34 either beneath the cam 30, or riding in the peripheral groove 31 or passing from one to the other of these two positions through either of the slots 32.

A vertically arranged spring 56 engaging the control lever 33 tends to hold the control lever elevated, rocking the rock shaft 39, and through its connections the rock shaft 20, to release the slide 17 so that the machine will stop at the end of the cycle in which it happens to be at any time. Thus by depressing the outer end of the control lever 33, bringing the pin 34 downward

through one of the slots 32, the machine is started, and as soon as the turntable is indexed, the slot 32 is brought out of registry with the pin 34, leaving the pin held by the spring 56 pressed against the under side of the cam 30, so that the control lever 33 is held in depressed condition until the number of cycles of the machine necessary to bring the oppositely disposed notch 32 in line with the pin 34 has been completed. As soon as this happens, the spring 56 raises the control lever 33, the pin 34 passing through one of the slots 32, causing the machine to stop at the end of that particular operative cycle. At any time during this normal operation of the machine with a plurality of operative cycles, the operator may swing the control lever 33 horizontally about its fulcrum 37 to bring the pin 34 out from beneath the cam 30, whereupon the spring 56 is free to lift it into clutch open position so that the machine will stop at the end of the cycle in which it happens to be when the control lever was so moved and without completing its full number of cycles. The operator may also at any time depress the lever 33 while in its position swung away from the cam 30, momentarily, to start a single cycle of the machine after which the machine will stop, provided the control lever has been allowed to rise by the time the clutch locking member 16 has arrived in position to impinge upon the slide 17 at the completion of a machine cycle.

While as shown this control mechanism has been applied to a duplex riveting machine, it is of course evident that it may be applied to other similar machines where it is desired for normal operation to have a plurality of machine cycles completed before the machine stops, with the further provision for interrupting this plurality of cycles at the end of any desired intermediate cycle, or of producing a single actuating cycle, as may be desired.

From the foregoing description of an embodiment of this invention, it should be evident to those skilled in the art that various changes and modifications may be made without departing from the spirit or scope of this invention.

I claim:

1. In combination with a machine adapted to perform a repetitive cycle of operations, of a one cycle clutch mechanism, a controller for such clutch mechanism actuatable to close the clutch and biased to clutch opened position, and a cam driven by said machine and having a cycle covering a plurality of machine cycles, and means supporting said controller for motion into or out of operative relation to said cam, said cam when said controller is in operative relation thereto retaining said controller in clutch closed position throughout a predetermined number of machine cycles and said controller when out of operative relation to said cam being free for actuation to clutch opened position prior to completion of said predetermined number of machine cycles.

2. In combination with a machine adapted to perform a repetitive cycle of operations, of a one cycle clutch mechanism, a controller for such clutch mechanism actuatable to close the clutch and biased to clutch opened position, and a cam driven by said machine and having a cycle covering a plurality of machine cycles, means supporting said controller for motion into or out of operative relation to said cam, said cam when said controller is in operative relation thereto retaining said controller in clutch closed position throughout a predetermined number of machine

cycles and when out of operative relation being free for actuation to clutch opened position prior to completion of said predetermined number of machine cycles, and yielding means tending to retain said controller in operative relation to said cam.

3. In combination with a machine adapted to perform a repetitive cycle of operations, of a one cycle clutch mechanism, an operator-actuable controller for said clutch mechanism mounted for motion in a pair of angularly related directions in one of which said controller controls said clutch and in which said controller is biased to clutch open position, a cam driven by said machine and into and out of operative relation to which said controller may be moved in the other of said directions, said cam having a cycle covering a plurality of machine cycles during which when said controller has been moved to clutch closed position and is in operative relation to said cam, said controller is retained in said clutch closed position, and said controller when out of operative relation to said cam being actuatable to open or close said clutch at the end of any desired machine cycle.

4. In combination with a machine adapted to perform a repetitive cycle of operations, of a one cycle clutch mechanism, an operator-actuable controller for said clutch mechanism mounted for motion in a pair of angularly related directions in one of which said controller controls said clutch, means biasing said controller in said one direction to clutch open position, a cam driven by said machine and into and out of operative relation to which said controller may be moved in the other of said directions, said cam having a cycle covering a plurality of machine cycles during which when said controller has been moved to clutch closed position and in its operative relation to said cam said controller is retained in said clutch closed position, said controller being free to be moved in said other direction out of operative relation to said cam at any time to permit said controller to be moved to clutch open position by said biasing means to permit said machine to be stopped at the end of an operative machine cycle short of said predetermined number of said machine cycles.

5. The combination with a machine having an indexing rotary turret, means for performing successive cycles of operations, means for indexing said turret between successive cycles, and a driving mechanism for driving said performing means, of a controller between said driving mechanism and said performing means including a one cycle clutch mechanism, said controller also including an operative member movable between a position to close said clutch mechanism and a position permitting said clutch mechanism to open at the end

of the cycle of operations, and a cam connected for indexing motion with said turret and with which said operative member may cooperate, said cam having a part for holding said operative member in clutch closed position for a predetermined number of said operative cycles when it has been moved initially to said clutch closed condition, and said member being mounted for motion out of cooperating relation to said cam whereby said performing means may be stopped at will at the end of an operative cycle short of said predetermined number of operative cycles.

6. In combination, an indexing turret, a rotary shaft to which said turret is fixed, means for performing an operation at a predetermined indexing station of said turret, means operated in time with said performing means to index said turret between successive operations, a machine control including a single operation clutch mechanism including a member movable between clutch closed position and a position permitting said clutch to open at the end of the operation, and a cam on said shaft having a peripheral groove and a channel leading from said groove to one end thereof, said member having a pin adapted to ride in said groove and channel and when in said groove said member being in said open clutch position and to engage said end when in clutch closed position, and means biasing said member to open clutch position so that in one angular position of said shaft said member is free to be moved between said clutch open and said clutch closed position.

7. In combination, an indexing turret, a rotary shaft to which said turret is fixed, means for performing an operation at a predetermined indexing station of said turret, means operated in time with said performing means to index said turret between successive operations, a machine control including a single operation clutch mechanism including a member movable between clutch closed position and a position permitting said clutch to open at the end of the operation, and a cam on said shaft having a peripheral groove and a channel leading from said groove to one end thereof, said member having a pin adapted to ride in said groove and channel and when in said groove said member being in said open clutch position and to engage said end when in clutch closed position, means biasing said member to open clutch position so that in one angular position of said shaft said member is free to be moved between said clutch open and said clutch closed positions, said member being mounted for yielding away from said cam whereby said member may be moved between said clutch open and clutch closed positions out of control by said cam.

ARTHUR R. HAVENER.
